UNITED STATES PATENT OFFICE.

CHARLES KITSCHELT, OF NEW YORK, N. Y., ASSIGNOR TO NICHOLAS MULLER'S SONS, OF SAME PLACE.

DESIGN FOR INKSTAND-SUPPORTS.

Specification forming part of Design No. **8,556**, dated August 3, 1875; application filed June 22, 1875.
[Term of Patent 7 years.]

CASE G.

To all whom it may concern:

Be it known that I, CHARLES KITSCHELT, of the city, county, and State of New York, have invented a Design for Inkstand-Supports, of which the following is a specification:

The nature of my design is fully represented in the accompanying drawings, to which reference is made, and in which—

Figure 1 is a side, and Fig. 2 a plan view representing my design aforesaid.

The base A is of oblong shape, and each of its ends, as from a to b, forms the one - half of a hexagonal figure, these semi-hectagons being connected at front by an entrant curve, e, the back being straight, as from b to b. At this back b is a vertical pillar, B, terminating at top in ornamental painted figures a'. Moreover, midway from each lateral surface of the pillar aforesaid may spring a downward and outwardly-curving arm, d, connecting with the back b by small vertical columns b'. In each end portion of the base A is a recess or cavity,

f, and at each end of the base aforesaid is a horizontal ornamental band, g, attached at one end to the contiguous column b', at the other to a similar column, c', at the front of the base and midway to a like column, f', at the extremity of the base.

The ends and front of the base are rabbeted, as shown at n, and from the upper edge of the rabbet the surface slopes upward and back, as shown at r, to the upper surface of the base.

I propose to make this design in bronze, or other metal or hard material.

What I claim as my invention is—

The design for an inkstand - support, comprising the oblong base A, formed with semi-hexagonal ends and the pillar B, the whole having the contour substantially as shown and described.

CHARLES KITSCHELT.
